Patented Oct. 31, 1922.

Inventor
John Albanese
By Percy H. Plant
Attorney.

UNITED STATES PATENT OFFICE.

JOHN ALBANESE, OF PROVIDENCE, RHODE ISLAND.

BRACELET.

Application filed March 24, 1922. Serial No. 546,530.

To all whom it may concern:

Be it known that I, JOHN ALBANESE, a subject of the King of Italy, residing at Providence, in the county of Providence and 5 State of Rhode Island, have invented certain new and useful Improvements in Bracelets, of which the following is a specification.

This invention relates to a bracelet structure of the type which comprises a series of units suitably connected together to form a flexible bracelet.

One object of the invention is to provide a device of this character wherein the several units are held in substantial contact with each other at all times to form a continuous structure in which the similarly constructed units are all of like appearance and are connected together without the intermediate position of separate link members.

Another object of the invention is to provide an improved structure of the character described wherein the connecting means for securing the units together are substantially concealed from view, while at the same time the parts are so arranged that a bracelet of great flexibility is provided.

A further object of the invention is to provide an improved form of connecting members for securing the several units together.

Other objects and advantages of the invention relate to certain improved details of construction and arrangement of the parts as will be more fully set forth in the detailed description to follow.

In devices of this character as heretofore commonly made it has been customary either to interpose separate link members of considerable size between the bracelet units in 40 such a manner that the completed structure presents the appearance of being formed of alternate links of radically different appearance, or to connect the bracelet units by means of connecting members so formed 45 as to leave a considerable space between the units. In fact with the constructions generally employed one or the other of these methods have been necessary in order to obtain a suitable degree of flexibility in the bracelet.

In my improved construction both of these objectionable features are overcome and a

structure provided wherein the units are held so closely together as to be in substantial contact with each other at all times while 55 permitting great flexibility of the parts.

Referring to the drawings:

Fig. 1 is a side view of the improved bracelet.

Fig. 2 is a plan view of a plurality of 60 units linked together.

Fig. 3 is a sectional view taken along the line 3—3 of Fig. 2.

Fig. 4 is a view of the structure similar to Fig. 3 except that links are arranged in 65 a curve to better illustrate the position of the parts when the bracelet is flexed, and,

Fig. 5 is a perspective view of one of the connecting members.

In the form of my invention illustrated 70 herewith 1 indicates generally one of the units of which the bracelet structure is formed which is provided with a flat base 2 and a continuous wall 3 formed integral with the base 2 and extending at substantially right angles relative thereto. Each unit is preferably pressed out from thin metal to form the base and wall portions thereof, and in the present instance the units are substantially circular in horizontal 75 cross section. Openings 4 and 5 are formed in opposite sides of each unit, each of these openings being formed on the line of intersection of said base and wall and sloping outwardly from the interior of the unit as 80 indicated at 6 to form in effect a knife-edge 85 7 in the base portion of the unit so that the adjacent units will have limited movement relative to each other about the knife-edge 90 7 of each unit.

The connecting members 8 for connecting the several units together are of similar construction and each comprise a head 10 curved to substantially fit against the interior surface of the wall of one of the units, a shank 95 11 extending from the convex side of the head 10 and having a kerf 12 cut therein to form separable prongs 13 at the end of said connecting member remote from the head 10.

In assembling the parts to form a complete structure the units are connected together by placing one of the connecting members 8 within one of the units and pass-

ing the shank 11 of the connecting member through the opening 4 in said unit and into the opening 5 formed in the next adjacent unit, whereupon the prongs 13 are separated 5 in any suitable or desired manner and pressed out into contact with the interior wall of the unit into which they were inserted. The second unit is connected to its next adjacent unit in like manner and 10 the process of operation continued until a sufficient number of the units have been connected together to form a bracelet of the desired length. The end unit 15 at one end of the bracelet is provided 15 with a resilient catch 16 adapted to be inserted in a socket 17 formed in a specially constructed unit 18 secured to the opposite end of the bracelet whereby the free ends 20 of the bracelet may be releasably secured together. The unit 18 is composed of a pair of units 1 permanently and rigidly secured together by means of a base plate 19 formed to provide a socket 17 for the reception 25 of the catch 16. Gems 20 are secured within the openings 21 in each of the units 1, as well as in the openings in the units 1 which comprise the specially constructed unit 18, by cementing them therein, by crimping the upper edge of the wall 3 there- 30 over or in any other suitable or desired manner. A seat 22 is preferably inserted in each unit 1 to serve as a support for each of the gems 20 as shown in Fig. 3 of the drawings, the seat being formed in any de- 35 sired manner which may be most suitably adapted for supporting the gem in proper position. In the present instance the seat is of inverted cup-shaped form adapted to fit loosely within the opening 21 in the unit 40 1 and presenting a flat upper surface 23 for supporting the gem. It will of course be understood that if the gems employed are of irregular shape, suitable openings may be formed in the upper surfaces of the seats 45 for the reception of such portions of the gems as may be necessary for supporting the same in proper position relative to the upper edge of the wall 2.

It will be seen from the above descrip- 50 tion taken in connection with the drawings appended hereto that I have provided a bracket of simple construction in which the several units are connected together by simple connecting members readily in- 55 serted in the units to positively hold the same in such position relative to each other as to present the appearance of an uninterrupted series of links of identical construction. The various units are moreover so 60 held relative to each other as to be in substantial contact at all times and conceal the connecting members from view, while at the same time the parts are so formed as to afford a considerable degree of flexibility 65 and permit a sufficiently free movement of

the units to adapt the same for fitting the wrist of the wearer.

What I claim is:—

1. A flexible bracelet, comprising a plurality of units each provided with a flat 70 base portion and a continuous wall integral with said base portion and extending at right angles therefrom, said wall being provided with diametrically opposite openings located adjacent the said base portion and 75 connecting members each provided with a head, a shank and separable prongs, passed through the openings in adjacent units for connecting said units and holding the same substantially in contact with each other at 80 all times while permitting flexing of the same.

2. In a flexible bracelet, a plurality of units each comprising a pressed metal shell provided with a flat base and a continuous 85 wall integral with said base and extending at right angles therefrom, said wall being provided with oppositely positioned openings formed in the meeting edges of said base and wall, said openings sloping out- 90 wardly from the interior to the outer edge of said base to form knife edges and connecting means passed through the openings in adjacent units and each provided with enlarged end portions shaped to conform with 95 the interior surface of said wall whereby the adjacent units are held in substantial contact with each other at all times, while permitting flexing of the same relative to each other both vertically and horizontally. 100

3. In a flexible bracelet, a plurality of units, each comprising a shell provided with a flat base and a continuous wall integral with said base and extending at right angles 105 therefrom, said wall being provided with oppositely positioned openings formed thereon on the meeting line of said wall and base; connecting members, each provided with a head, a shank portion and separable prongs, 110 insertable in the openings in adjacent unit, whereby upon separation of said separable prongs the adjacent units are held in substantial contact with each other while permitting flexing of the same relative to each other and the said connecting members, and an ornamental gem seated in each of said units above the free ends of said connecting means. 115

4. In a flexible bracelet, a plurality of 120 similarly constructed gem supporting units each formed with a flat base portion and a continuous wall integral with said base and extending at right angles therefrom for engaging and supporting said gem, said 125 wall being provided with oppositely positioned openings adjacent to the base; and connecting members for securing adjacent units against separation while permitting limited movement of the same relative to 130

each other, each of said connecting members comprising a head shaped to conform with the interior surface of the wall of one of said units, a shank and separable prongs,

5 said connecting members being each passed through adjacent openings in adjoining units and having the separable prongs sepa-

rated to contact with the interior wall of one of said units whereby the units are held in substantial contact with each other at all ¹⁰ times.

In testimony whereof I have affixed my signature.

JOHN ALBANESE.
